COVER OR LID FASTENER

Charles P. Bobst, Anamosa, Iowa

Application May 16, 1940, Serial No. 335,605

5 Claims. (Cl. 292—213)

This invention relates to an improved construction of fastener particularly designed for use on the ends of egg case covers for readily securing the cover on an egg case.

More particularly, it is an aim of this invention to provide an improved construction of fastener formed from a strand of wire having hook shaped ends adapted to yieldably engage beneath and pierce a batten or cleat on a case or box for detachably securing a cover in position thereon.

More particularly, it is an aim of the invention to provide an improved construction of fastener, formed from a single strand of wire, which is so constructed as to include spring coils formed in corresponding legs thereof which cross adjacent their terminals so that said terminals may be retracted by being pressed toward each other and projected, when released, by the coil springs formed in said legs.

Other objects and advantages of the invention will hereinafter become more fully apparent from the following description of the drawing, which illustrates a preferred embodiment thereof, and wherein:

Figure 1 is a bottom plan view of a cover or lid having a fastener applied to each end thereof, constructed in accordance with the invention.

Figure 2 is an end view in elevation showing one of the fasteners positioned to engage a cleat or batten on a box or crate for retaining a cover in position thereon.

Figure 3 is an enlarged vertical sectional view taken substantially along the plane of the line 3—3 of Figure 2.

Figure 4 is an enlarged longitudinal sectional view taken substantially along the plane of the line 4—4 of Figure 1, and

Figure 5 is a horizontal sectional view taken substantially along the plane of the line 5—5 of Figure 3.

Referring more particularly to the drawing, wherein like reference characters designate like or corresponding parts throughout the different views, 10 designates a cover or lid for an egg case and 11 designates generally a portion of an egg case or other container having an end wall 12 provided with a batten or cleat 13 on its outer side and extending downwardly from its upper edge. It is to be understood, that the opposite end of the case or container 11 is provided with a similar wall 12 and batten 13, not shown. Cover 10, at its ends, is provided with the depending reinforcing strips 14 which are adapted

to rest on the upper edges of end walls 12 and cleats 13 in the position, as best illustrated in Figure 3.

A strap hanger 15 is secured to the upper side of each end of the cover 10 by means of the fastenings 16 and is provided with a tapered hanger portion 17 which depends downwardly along the outer side of each of the reinforcing strips 14. Hanger portions 17 terminate in the restricted turned back portions 18 which form loops 19.

The fasteners, designated generally 20, each comprise a strand of wire having an intermediate portion 21 loosely mounted in a loop 19 and pivotally supported thereby on a hanger 15. Corresponding legs 22 project substantially at right angles from the ends of the intermediate portion 21 and are looped to form a pair of inwardly projecting corresponding coil springs 23.

From the coil springs 23, the legs 22 extend inwardly and downwardly past one another with their ends bent downwardly, inwardly and back upon themselves to form the hook shaped members 24 having the upwardly projecting pointed prongs 25, as best seen in Figure 3. The pair of loops forming the coil springs 23 are connected by means of a link 26 to prevent the springs from moving away from one another when the fastener 20 is actuated, as will hereinafter become more fully apparent.

It is to be understood that the fasteners 20 at the ends of the cover 10, as illustrated in Figure 1 are identical and for this reason only one of the fasteners has been described.

To apply and secure the cover 10 to the case or container 11, the fasteners 20 are swung outwardly and away from the cover 10 after which the cover is positioned on the case 11 with the strips 14 resting on the upper edges of the end walls 12 and cleats 13. The fasteners 20 are then swung downwardly and toward the cleats 13 and the pairs of hook shaped portions 24 are pressed inwardly toward each other thereby causing said hook shaped portions to move downwardly so that the prongs may be moved to a position beneath the cleats 13. The pairs of hook shaped portions 24 are then released so that their springs 23 can move the portions 24 away from each other and upwardly to cause the pointed ends of the pairs of prongs to pierce the bottom edges of the cleats or battens 13, in the manner as illustrated in Figure 3, to securely fasten the cover 10 to the case or container 11. To detach the cover 10, it is only necessary to press inwardly on the pairs of hook shaped mem-

bers 24 so that the pointed ends of the prongs 25 will be retracted and drawn downwardly and out of engagement with the cleats 13 after which the fasteners 20 can be swung outwardly to release the cover 10.

In Figure 4, one of the fasteners 20 is shown in a folded position beneath and substantially parallel to the cover 10 with the prongs 25 engaging the inner edge of the strip 14, the prongs 25 being moved to this position after the hook shaped portions 24 are compressed or pressed inwardly, as heretofore explained. In this position, the cover 10 may be stacked on other similar covers provided with similar fastenings 20 for storage or shipping purposes.

The fastener 20 together with the strap hanger 15 may obviously be used singularly on other types of covers for containers such as hinged covers where the opposite end is hingedly connected to the container and in which case only 20 a single fastener is required.

Various modifications and changes in the construction and arrangement of the parts forming the invention are contemplated and may obviously be resorted to without departing from the spirit and scope of the invention as herein-after defined by the appended claims.

I claim as my invention:

1. A cover or lid fastener comprising a fastener having an intermediate portion pivotally connected to a cover, legs projecting from said intermediate portion and having inwardly turned hook shaped terminals forming upwardly projecting pointed prongs, said legs being crossed intermediate of their ends, and coil springs formed in the legs of said fastener and disposed adjacent the intermediate portion and remote to said terminals for retaining the prongs in a projected position, said coil springs being disposed above the hook shaped terminals, and said prongs being retractable by drawing the hooked shaped portions inwardly relatively to each other.

2. A cover fastener comprising a strap of sheet metal or the like secured to a cover or lid, a fastener, formed from a single strand of wire having an intermediate portion pivotally connected to said strap and supported thereby on said lid, legs projecting from the ends of the intermediate portion and having inwardly turned hook shaped terminals, said legs being crossed 50 adjacent their terminals and being looped to

form coil springs, disposed adjacent to said intermediate portion for yieldably urging the hook shaped terminals upwardly to a projected position, said terminals being retractable by being

5 pressed inwardly relatively to each other for positioning said hook shaped ends beneath a projection on a container, and said springs urging the hook shaped ends upwardly into engagement with said projection for fastening the lid 10 in a closed position on the container.

3. An attachment for use with a container provided with a batten on its outer side and with a closure, comprising a fastener formed of a strand of resilient wire having an intermediate

15 portion pivotally connected to said closure, said fastener having downwardly and inwardly extending legs crossing each other adjacent their terminals, said terminals being hook shaped, and said legs, adjacent said intermediate portion and above the hook shaped ends, being looped to form coil springs for yieldably retaining the hook shaped ends in a projected position, said hook shaped ends being disposed beneath said batten for yieldably engaging the underside thereof to retain the closure in a closed position, and said 25 terminals being compressible relatively to each other for retracting said hook shaped ends downwardly and out of engagement with the batten.

4. A closure fastener comprising a strand of 30 wire having an intermediate portion pivotally connected to a closure, curved legs extending from said intermediate portion and crossing adjacent their free ends, said free ends being hook shaped, and said legs, adjacent said intermediate portion, being looped to form coil springs for projecting said hook shaped ends, said coil springs being disposed above the hook shaped ends, said hook shaped ends being adapted to engage beneath a batten or cleat on a container 35 for retaining the closure in position thereon, and said hook shaped ends being movable toward each other for retracting them downwardly and out of engagement with the batten or cleat to release the closure.

5. A fastener as in claim 4, said hook shaped ends being turned inwardly and upwardly relatively to the closure and being provided with pointed free ends adapted to be embedded in the underside of the cleat or batten.

CHARLES P. BOBST.
